C. LAMBERT

HARNESS STOP MOTION

Filed Feb. 12, 1926

FIG. 1

FIG. 2

The diagram illustrates a mechanical assembly. A base plate **D** is shown at the bottom. A vertical support **M** is attached to the top of the base plate. A horizontal beam extends from the top of the support **M**. The distance from the top of the base plate to the center of the horizontal beam is labeled **21**. The distance from the center of the horizontal beam to the end of the beam is labeled **20**. The distance from the end of the horizontal beam to the vertical support **M** is labeled **20**. A triangular component is attached to the base plate **D** and the vertical support **M**. The distance from the base of the triangle to the vertical support **M** is labeled **23**. The distance from the base of the triangle to the point where it meets the base plate **D** is labeled **24**. The distance from the base of the triangle to the point where it meets the vertical support **M** is labeled **25**. A vertical line extends downwards from the center of the horizontal beam, labeled **30**. A horizontal line extends from the end of the horizontal beam, labeled **77**. A curved line labeled **77** is also shown.

UNITED STATES PATENT OFFICE.

CYRILLE LAMBERT, OF LAWRENCE, MASSACHUSETTS

HARNESS STOP MOTION.

Application filed February 12, 1926. Serial No. 87,784.

This invention relates to looms, and its purpose is to stop the loom in case either the means of suspending or holding up the harness breaks or becomes slack, or the 5 means for pulling it or holding it down breaks or becomes slack.

As shown in the drawings and specification, it is applied to what is known as the Knowles head motion but it may be used 10 on any type of loom where bottom straps are used to pull the harness down.

I am aware that various means have been devised for stopping a loom when the overhead suspending connection breaks and the 15 harness drops upon suitable trip mechanism, but this device will operate when either the top or bottom harness straps break or become loose.

In the drawings, Fig. 1 is a side elevation 20 showing those parts of a loom only which are necessary to understand my invention.

Fig. 2 is a vertical section looking from the left, on the line 2—2 of Fig. 1.

Fig. 3 is an elevation of one of my drop 25 hooks.

Figs. 4, 5 and 6 are diagrammatic views showing the connection of various parts and what occurs when certain of the controlling straps or members break.

30 Fig. 7 is an elevation similar to Fig. 1, showing in detail a modification of the connections between the interfering finger and the trip lever.

Fig. 8 shows a modified form of drop hook.

In the drawings, C represents a loom in which there is a warp beam 1, a whip roll 2, cross girt 3 and oscillating feelers 4, 4, in operative relation with drop wires 5, all of 40 well known types.

The oscillating feelers are connected with mechanism of well known character whereby when an oscillating feeler is stopped, the loom is stopped by suitable connecting mechanism.

45 Each harness is represented by D, and each harness is supported by one or more top harness straps such as 20 which pass over loose pulleys 21 and are attached to one arm of the harness jack 22.

At the bottom there are bottom harness straps such as 23, 23, which are connected and attached to another strap 24 which passes over a loose pulley 25. Another bottom harness strap 26 connects with the other 50

arm of harness jack 22 and passes over a loose pulley 27.

Between the ends of the straps 24 and 26, is a horizontal wire 30 which is ordinarily kept taut and level by the suitable adjustment of the top and bottom harness straps. 60

The above described construction is all old and forms part of the well known Knowles head motion.

For each harness and harness wire such as 30, I provide a drop hook B which as shown, has a hole 40 through which a wire 30 passes, and at the top a hook 41 which when the hook is held up in normal position by its wire 30 rests just over the long arm 50 of a trip lever A.

Each drop hook B passes through suitable guides in a guide box 45 which is shown as attached to cross girt 3, and as having a lever supporting arm 46 on which at 51 trip lever 50 pivots.

G represents an interfering finger which is carried by a curved arm 60 pivoted at 61 to a suitable bracket 62 fixed to a stationary part of the loom frame 6.

80 This finger G is so positioned that it can move up in front of one of the oscillating feelers 4 and stop its oscillation, but is ordinarily held down as by means of a counterweight 70 forming part of connecting means H which connects the interfering finger with the short end 52 of trip lever A.

This connecting means includes a connecting rod 71 pivoted at 72 to arm 60, and carries the counterweight 70. It, preferably 90 also by means of a turnbuckle 73, is attached to the end of short arm 52.

By means of the counterweight 70 and turnbuckle 73, and by changing the weight of 70, an interfering finger G is normally 95 held out of and below the path of an oscillating feeler 4 and the long arm 50 of trip lever A is held up just under the hooks 41, 41 of the various drop hooks B.

Fig. 4 shows the normal position of the 100 parts while Fig. 5 shows what happens if one of the lower harness straps such as 23 breaks, while Fig. 6 shows what occurs if one of the top harness straps such as 20 breaks.

105 In either case, the horizontal wire 30 connected with that particular harness will drop and instead of holding up a drop hook B it will allow it to fall, assisting with its own weight.

The weight of hook B will depress long arm 50 and lift short arm 52 of trip lever A and thereby raise interfering finger G into the path of an oscillating feeler 4, thereby stopping the loom.

As shown at F in Fig. 8, I may use a drop hook F which has a hook 90 at the top but at the bottom a slot 91 instead of a hole.

As shown in Fig. 7, I may, instead of connecting means H, use connecting means L in which the interfering finger 80 is carried at the end of a slide rod 81, slideable on one of the vertical members or a post 7 secured to the back girt 8 of the loom. As shown, 81 has slots 83 through which pass guide screws 84 allowing it to slide.

Short arm 52 passes through a loop 85 on rod 81.

The straps 20, 23, 24, 26, pulleys 21, 25, 27, harness jack 22 and wires 30 may be considered collectively as harness controlling means and are indicated by M.

I claim:

1. In a loom having an oscillating feeler so connected that when it is stopped, the

loom stops, a harness supported at the top by top harness straps and held at the bottom by bottom harness straps and a horizontal wire; the combination of a drop hook supported by said wire over one arm of a trip lever; said trip lever; an interfering finger; means connecting the interfering finger with the other arm of the trip lever of such character that when a drop hook drops with the wire, the interfering finger is moved in the path of the oscillating feeler and the loom is stopped.

2. In a loom having an oscillating feeler so connected that when it is stopped, the loom stops, a harness, harness controlling means including a horizontal wire; the combination of a drop hook supported by said wire over one arm of a trip lever; said trip lever; an interfering finger; means connecting the interfering finger with the trip lever of such character that when a drop hook drops with the wire, the interfering finger is moved in the path of the oscillating feeler and the loom is stopped.

CYRILLE LAMBERT.
